United States Patent [19]
Riumbau

[11] Des. 273,580
[45]  Apr. 24, 1984

[54] COMBINATION BATTERY CHARGER AND TESTER

[76] Inventor: Conrad L. Riumbau, 79-11 41 Ave.
#A617, Elmhurst, N.Y. 11373

[] Term: 14 Years

[21] Appl. No.: 297,200

[22] Filed: Aug. 28, 1981

[52] U.S. Cl. D13/5; D10/77
[58] Field of Search D13/5, 24, 30, 28, 27;
320/2, 3, 4, 5; D10/77; 339/252

[56] References Cited

U.S. PATENT DOCUMENTS

D. 252,502 7/1979 Kelly D10/77

D. 257,882 1/1981 Rawson et al. D13/5
3,492,627 1/1970 Tauer 339/252
4,184,580 1/1980 Ellis, Jr. 320/2

Primary Examiner—Wallace R. Burke
Assistant Examiner—Lynn Wilder

[57] CLAIM

The ornamental design for a combination battery charger and tester, substantially as shown and described.

DESCRIPTION

FIG. 1 is a perspective view of a combination battery charger and tester showing my new design, with a battery secured thereto, in phantom, for illustrative purposes only and forming no part of the claimed design; FIG. 2 is a right side elevational view thereof; FIG. 3 is a rear elevational view thereof; and FIG. 4 is a bottom plan view thereof.

FIG.1

FIG.2

FIG.3

FIG.4